UNITED STATES PATENT OFFICE

124,554

DESIGN FOR A TWO-PIECE DRESS

Clyde Riggs Perkins, Tucson, Ariz.

Application August 29, 1940, Serial No. 94,722

Term of patent 7 years

To all whom it may concern:

Be it known that I, Clyde Riggs Perkins, a citizen of the United States, residing at Tucson, in the county of Pima and State of Arizona, have invented a new, original, and ornamental Design for a Two-Piece Dress, of which the following is a specification, reference being had to the accompanying drawings, forming a part thereof.

In the drawings:

I claim:

The ornamental design for a two-piece dress, as shown.

CLYDE RIGGS PERKINS.
